UNITED STATES PATENT OFFICE.

JOSEPH J. GAHN, CHARLES B. WILKES, JR., AND JOHN P. DAVIS, OF ST. LOUIS,
MISSOURI.

PROCESS OF DUPLICATING TYPEWRITING AND THE LIKE.

Application filed September 20, 1920. Serial No. 411,633.

To all whom it may concern:

Be it known that we, JOSEPH J. GAHN, CHARLES B. WILKES, Jr., and JOHN P. DAVIS, citizens of the United States, residing at the city of St. Louis, in the State of Missouri, have invented certain new and useful Improvements in Processes of Duplicating Typewriting and the like, of which the following is a specification.

10 This invention is a method of, and apparatus for, duplicating typewriting and the like. It is adaptable to any one of numerous machines on the market, but in the drawings is depicted in connection with 15 a machine commonly known as a multigraph.

One result of this invention is the saving effected by omitting the automatic ribbon-feed from the machine, which being more or less complicated and composed of a plurality of parts is an expensive feature of present machines. It is unnecessary in connection with the present invention, and its omission is an economy in the construction 25 of the machine, besides which much time is saved in operation by its no longer being necessary to adjust the ribbon, due to its uneven movement and its not retaining its correct position.

30 Due to slippage of the ribbon in machines of this kind now in use, a long letter is never of uniform color throughout its length, but in parts is of a heavier or deeper color than elsewhere. For instance, if 35 a black ribbon be used, part of such a letter will be black and part gray, which is a very undesirable effect. If, then, the name and address be filled in with a typewriter, either another part of black or a third 40 shade is produced. This objection is obviated by the present invention.

An advantage produced by the present invention is that it more nearly than any other method produces in facsimile letters 45 the imitation of handwork on a typewriting machine, due to its giving the light and heavy effect on certain letters, thus imitating the inequalities of touch on different letters by most typewriter operators.

50 This invention does away with the use

of the ordinary multigraph ribbon, thus saving the great expense of purchasing them. It makes it possible simultaneously to print letter-heads from printers' type and fac-simile letters from typewriter type. By 55 simultaneously is meant in one continuous operation, in which, while a piece of paper is fed through the machine, the rotation of the cylinder prints in succession the letter-head as if done on a job press and then the 60 fac-simile letter from typewriter type. These steps may be performed in either order, and it is immaterial whether the machine be of the rotary type or some other— 65 the principle and method are the same.

This invention more than doubles the quantity of letters that can be produced in a given time. This has been determined by actual trial and demonstration. This 70 decreases their cost.

Due to the fact that this invention substitutes a piece of ordinary China silk for the expensive multigraph ribbons, and due, also, to the fact that one yard of this silk (costing about forty cents) will produce 75 more letters than eighteen or twenty dollars' worth of the customary multigraph ribbons, the great economy attained by this invention is evident.

Mechanical details are herein provided 80 for easily attaching the said silk to, and detaching it from, the roller or other surface carrying the type.

In the accompanying drawings forming 85 part of this specification, in which like numbers of reference denote like parts wherever they occur,

Figure 1 is a top plan view of a multigraph machine, with the ordinary ribbon and automatic ribbon-feeding mechanism 90 omitted and the silk, mentioned above, in place, with means for holding it on the drum;

Figure 2 is a sectional view on the line 2—2 in Figure 1, looking in the direction indicated by the arrows;

Figure 3 shows the arrangement to print letterhead and fac-simile letter by one continuous operation; and

Figures 4 and 5 illustrate in section addi- 100

tional and alternative means for attaching the silk to the roller.

The frame 1 of the machine supports the roller 2 in the usual manner, so that the roller 2 can be freely rotated backward or forward by handle 3. The type-cylinder or roller 2 contains grooves 4 in its surface, in which the type are set. Due to this way of setting the type, they are in yieldable relation to the type-cylinder or roller 2, instead of forming a relatively hard and firm or solid body like the type in a job press. It is because of this yieldingness of the type that the effect of imitation of typewriting is produced, the type in a typewriter wavering more or less as struck and when printing, and the type set in grooves 4 likewise yielding as type-cylinder 2 revolves. It is, also, due to this yielding of the type in this machine that the silk 5 hereinabove mentioned and hereinafter described can be successfully used instead of a ribbon. If the type were set firmly and solidly, as in a job press, the imprint through the silk 5 would not produce a true and good imitation of typewriting, but as used according to the method herein set forth the imitation of typewriting is perfect and superior to any heretofore known.

30: This method consists in first washing the silk 5 with water, which removes from it gloss or lint or other appurtenances that unfit it for the use herein described. After such washing, it performs its function in lieu of a ribbon with complete efficiency, but will not do so without washing.

The silk 5 is then attached to the type-cylinder 2 in any desired manner. In Figure 1 it is shown attached thereto by hollow rods 6, which are borne by spring-sockets 7, at present found (for a different purpose) in such machines on the market. It is immaterial whether such spring-sockets are on the ends of rods 6 or on frame 1 of the machine. Such spring-sockets 7 permit slight rotation by hand of rods 6 and consequent adjustment, if desired, of the silk 5. Attachment of the silk 5 to type-cylinder 2 by an arrangement of such rods 6 permits, also, the gradual moving out for use of a supply of silk carried in the first place in a roll on one of the said rods 6. The silk 5 may at its ends be attached to the rods 6 in any suitable manner, either by being tucked therein and held by rods 8 or otherwise.

60: Other means for attaching the silk 5 to cylinder 2 are the clips 9 shown in Figures 3 and 4 and the rod 10 shown in Figure 5. Still other means for the same purpose may be employed. A roller 6 may be used to hold one end of the silk 5 and clips 9 or rod 10 the other or other mutations are possible.

65: The ink used is a kind of a quick-dry-

ing printer's ink especially adapted for this particular purpose, which comes from the reservoir 11 and is applied by the ink-rollers 12.

When it is desired to print a letterhead 70 and a facsimile letter by one operation, the type 13 for printing the letterhead are left exposed, as shown in Figure 3, but the silk 5 is placed so as to cover over the type from which the fac-simile letter is to be printed 75 and attached by clips 9 or in any other suitable manner. The ink is the same for type 13 as for the letter, but type 13 prints the letterhead like a job press, while the interposition of silk 5 causes the imprint of 80 the letter to be the fac-simile of typewriting.

The fact that the silk 5 is stationary, instead of the ribbon automatically traveling as customary in such work, produces 85 greater evenness of color, because slippage is prevented. Nevertheless, the thinness of the silk, compared to the ordinary ribbon, permits a more satisfactory impression of the type through the silk 5 than through 90 the relatively thicker and heavier ribbon, resulting in a closer imitation of the appearance of real typewriting. The silk has a quality or characteristic of becoming a matrix as the type presses thereinto, thus 95 giving the desired quality to the imprint.

The silk 5 can be adjusted slightly, if desired, on cylinder 2, and will preferably be turned over and from end to end, thus 100 doubling its life and utility.

Material other than silk may be used for the stationary textile face 5, provided that it is thin and quite impressionable and yielding easily to take a form under pressure and to yield that form and assume another under new pressure, and may be either textile or fibrous.

105: It will be observed that this method and apparatus provides for the material 5 to be held much more in proximity to the face 110 of the type than is possible with a traveling ribbon.

When the handle 3 is turned, pressure is applied in the usual way.

Having thus described this invention, we 115 hereby reserve the benefit of all changes in form, arrangement, order, or use of parts as it is evident that many minor changes may be made therein without departing from the spirit of this invention or the scope of 120 the following claim.

We claim:

The herein described method of printing letterheads and facsimile letters in one operation which consists in mounting the type 125 for the letterhead firmly and solidly on a printing drum and in mounting the type for the body of the letter loosely in the drum so as to slightly yield during the printing operation, covering the type for 130

the body of the letter with a sheet of silk which has previously been washed to remove the gloss and lint, fastening the ends of the silk to the drum to hold it stationary ter, and then pressing the inked parts against the surface to be printed thereby. ¹⁰

In testimony whereof we hereunto affix our signatures.

- 5 relative to the body of type covered thereby, applying ink direct to the type of the letter-head and, also, to the portion of the silk covering the type for the body of the let-
